JUMP ROPE

Filed Feb. 15, 1922

INVENTOR,
George C. LaSares,
BY

Harry W. Brown,
ATTORNEY.

UNITED STATES PATENT OFFICE.

GEORGE C. LA SARES, OF SPRINGFIELD, MASSACHUSETTS, ASSIGNOR TO C. E. BRADLEY CORPORATION, OF BRATTLEBORO, VERMONT, A CORPORATION OF VERMONT.

JUMP ROPE.

Application filed February 15, 1922. Serial No. 536,800.

To all whom it may concern:

Be it known that I, GEORGE C. LA SARES, a citizen of the United States of America, residing at Springfield, in the county of 5 Hampden and Commonwealth of Massachusetts, have invented certain new and useful Improvements in Jump Ropes, of which the following is a specification.

This invention relates to improvements in 10 jump ropes.

The invention relates to a new and novel means of attaching the rope or cord to the handle part of the device, whereby, when the handle is gripped the cord is permitted 15 to turn or revolve freely in the handle without any possibility of the cord becoming twisted or kinked.

The invention, broadly, comprises means for rotatably mounting the gripping handle 20 on a spindle device, which device is fixedly connected to the rope cord.

Referring to the drawings:

Fig. 1 is an elevational view, partly in section, showing the rope and the means of 25 attaching the same to the handle and the gripping portion of the handle being shown rotatably connected to the cord.

Fig. 2 is a vertical transverse sectional view on the line 2—2 of Fig. 1.

30 Referring to the drawings in detail:

1 designates the cord or rope proper which is composed of a suitable material as a woven window weight cord. 2 is the rotatable handle or gripping portion which the 35 user grasps when the rope is used. 3 is the shaft or spindle on which the handle 2 is mounted. This spindle is connected to the shaped member 4 that is formed with an opening through the axis thereof. The 40 member 3 extends into the part 4 and is attached thereto by means of the pin 5. The ends of the cord 1 are connected to parts 4, preferably by gluing as indicated by the lines 6. When the user grasps the handles 45 2 and rotates the cord over the head and below the feet as the device is generally used, the spindle 3 will turn loosely in the handle 2 thus preventing any possibility of the cord becoming twisted and also making it easier

for the operator to use. The end of the 50 spindle 3 is formed with a knob 7 for retaining the same in place on the spindle. It will be seen from this description that I have provided a very simple and inexpensive way of connecting the rope of the device to the handle permitting the cord to 55 turn freely therein.

What I claim is:

1. A jump rope construction, having in combination, with the rope, of handle members formed with openings therein, devices loosely mounted in the openings of the handle members, devices formed to receive the loosely mounted devices in the openings of the handles, means for securing the two devices together, the second mentioned devices serving to secure the ends of the rope thereto, whereby when the rope is rotated the handle members will remain stationary and the loosely mounted devices therein will turn 70 with the rope as described.

2. In a jump rope construction, the combination with the rope thereof, of a member formed with an opening to receive an end of the rope, a spindle member, means for connecting the spindle to the rope receiving member comprising a pin passing through the member and the spindle, a handle member proper rotatably mounted on the spindle whereby when the rope is turned the 75 spindle will turn or rotate in the handle member.

3. In a jump rope construction, the combination with the rope, of handle members formed with openings therethrough, spindles loosely mounted in the openings and projecting beyond the ends towards the ends of the rope, members having openings therethrough to receive the projecting ends of the spindles, means in the members for securing the same to the spindles, the ends of the rope being fixedly secured to the members and rotating therewith and the spindles when the rope is rotated whereby the handle members will remain stationary in the hands 90 of the user, as described.

GEORGE C. LA SARES.
